UTILITY STOVE

Victor R. Wagner, Lakewood, N. Y., assignor to
 Carolyn L. Wagner and Victor Roy Wagner, Jr.,
 executors of said Victor R. Wagner, deceased

Application June 22, 1948, Serial No. 34,512

1 Claim. (Cl. 126—9)

1

This invention relates to utility stoves, and more particularly to an improved stove designed for outdoor use, which can be inexpensively constructed and made conveniently collapsible to occupy limited space in storage and transportation.

This improved utility stove, designed to serve the comfort and convenience of campers and sportsmen, can be inexpensively fabricated from relatively light gauge sheet metal, is light in weight, and can be carried and transported in collapsed condition as a compact, unitary package. When the stove is to be used, the collapsed and nested parts thereof can be erected and assembled in approximately a minute or less time to provide a highly efficient heating unit wherein combustible fuel such as coal, charcoal, wood or similar fuel, may be burned upon a fire grate member associated therewith.

This improved stove is also provided with a top panel which may be readily adjusted to control the air draft, and thereby control the rate of fuel combustion, as desired. The adjustable top panel also provides a hot plate upon which a cooking utensil or the like may be supported. The improved stove is also provided with a receptor pan in which the burned ash from the superimposed fire grate is collected.

This improved utility heating unit may be constructed in any desired size ranging from approximately four inches in width and breadth and eight inches high, to such larger sizes as may best suit the convenience of the camper or sportsman. The unit may be provided with a removable carrying handle whereby the fully assembled unit may be conveniently transported. The parts forming this utility unit are so constructed that they may be conveniently and quickly detached from each other and nested together in a compact manner to provide an assembled package less than 1 inch thick and of limited area.

Other objects and advantages of this invention will become apparent as the disclosure proceeds.

Although the characteristic features of the invention will be particularly pointed out in the claim appended hereto, the invention itself, and the manner in which it may be carried out, may be better understood by referring to the following description taken in connection with the accompanying drawings forming a part hereof, in which

Fig. 1 is a perspective view of the improved utility stove as it appears when fully assembled.

2

Fig. 2 is a fragmentary perspective view to illustrate the manner in which the enclosing wall panels thereof are detachably connected together, this view being taken on line 2—2 of Fig. 1.

Fig. 3 is a horizontal cross sectional view of the stove unit as the same would appear when viewed along line 3—3 of Fig. 1.

Fig. 4 is a perspective view of the top plate forming panel.

Fig. 5 is a perspective view of the support panel, two being provided.

Fig. 6 is a perspective view of the suspended panel, of which two are provided.

Fig. 7 is a perspective view of the grate forming member.

Fig. 8 is a perspective view of the ash receptor pan.

Fig. 9 is a perspective view of a detachable carrying handle, which may be associated with the stove unit.

Fig. 10 is a perspective view of the stove forming parts as they appear when nested together in a compact package for convenient storage and transportation.

Fig. 11 is a longitudinal cross sectional view of the nested stove forming parts as the same appears when viewed along line 11—11 of Fig. 10, and

Fig. 12 is a transverse cross sectional view of the nested stove forming parts as the same would appear when viewed along line 12—12 of Fig. 10.

Similar reference characters refer to similar parts throughout the several views of the drawings and specification.

Referring to the drawings, this improved utility stove is formed from a plurality of shaped sheet metal parts comprising a pair of oppositely arranged support panels 10 on which the pair of suspended panels 20 are hung to provide a four-walled enclosure. A sheet metal grate member 30 is positioned within the walled enclosure formed by the support panels 10 and the suspended panels 20. The stove unit also includes an ash receptor pan 40 which additionally serves as a base upon which the support panels 10 are seated. A top panel 50 of sheet metal shaped to telescope over the upper ends of the enclosure forming panels 10 and 20, provides a hot plate upon which food may be broiled, or a cooking utensil supported.

The two sheet metal support panels 10 are each shaped in the general form illustrated in Fig. 5 to provide a wall forming section 11 having an inturned flange 12 along each of the vertical

edges thereof. The lower edge 13 of the paired support panels 10 are designed to seat upon the base wall 41 of a receptor pan 40. The receptor pan 40 has a pair of upstanding flanges 42 which are sprung slightly inwardly so as to exert a frictional grip against the flanges 12 of the support panels 10 as seated on the base wall 41 of the receptor pan. The receptor pan flanges 42 may be provided with suitable blisters or pimples 43, complementary to blisters or pimples 14 formed in the panel flanges 12 adjacent the lower ends thereof, to insure positive frictional attachment of the support panels 10 to the receptor pan 40.

Each of the paired suspended panels 20 are of somewhat less height than the support panels 10, 15 and are hung from the spaced flanges 12 of the paired support panels 10 in space relation to the receptor pan 8, as shown more particularly in Fig. 1. Each suspended panel 20 comprises a wall forming section 21 presenting a pair of projecting metal buttons 22 along each vertical side edge thereof. The buttons 22 are designed to be inserted into complementary bayonet slots 15 formed in the adjacent overlying flanges 12 of the support panels 10. Each suspended panel 20 is 25 also provided with an inturned flange 23 extending horizontally along the lower edge thereof to provide a support for the grate member 30.

The suspended panels 20 are detachably connected to the space support panels 10 by inserting each lock button 22 through the enlarged head portion 15' of the adjacent bayonet slot, and then lifting the suspended panels 20 upwardly so that each lock button 22 will be retained in the contracted neck portion 15" of its associated bayonet slot. When thus assembled, the upper edge 24 of the suspended panels 20 will be substantially in the same plane as the upper edge 16 of the support panels, as shown more particularly in Fig. 1. The suspended panels 20 may be detachably locked in suspended position by the provision of latch dogs 17. Each latching dog 17 is hinged as by pivot pin 18 to the flange 12 of the support panel 10. The latch dogs 17 are positioned directly below the lower edge of the suspended panels 20 as mounted in assembled position, and are designed to be swung upwardly with the cam edges 17' thereof in frictional camming engagement with the under face of the inturned flanges 23 of the adjacent suspended panel 20. When the latch dogs 17 are in up-swung position, as shown in phantom lines in Fig. 2, the suspended panels 20 are supported thereby in rigidly assembled and locked position. The latch dog 17 may, however, be down-swung as desired to disconnect the enclosure forming panels 10 and 20.

The grate member 30 comprises a flat plate of sheet metal having a series of air draft holes 31 punched therein. The grate member 30 is of generally rectangular shape, and of a size so that it may be dropped into the erected enclosure forming panels 10 and 20, so as to seat upon the inturned flanges 23 of the suspended panels 20, as shown more particularly in Fig. 3. As thus supported, the grate member 30 is spaced above the base wall 41 of the receptor pan 40 so as to permit draft air to be drawn through the open space above the upstanding flanges 42 of the receptor pan 40, through the grate openings 30, and into the fire chamber defined by the assembled enclosure forming panels 10 and 20. A series of air openings 25 may also be punched through the wall forming section 21 of the suspended panel 20 to insure adequate air draft.

The top panel 50 is formed of a light gauge 75

metal and comprises a plate forming section 51 having a pair of depending flanges 52 designed to telescope over the upper edges 16 and/or 24 of the enclosure forming panels 10 and 20 respectively. The flanges 52 serve to guide the lateral sliding movement of the top panel 50, whereby the size of the chimney opening *a* as shown in Fig. 1, may be varied, thereby effecting a corresponding variation in the air draft and the rate of combustion of the fuel supported upon the grate member 30.

This improved utility stove is made from inexpensively formed sheet metal parts which can be manufactured at very low cost. The stove may be assembled in a matter of a minute or less by attaching the suspended panels 20 to the support panels 10, and locking the suspended panel 20 in position by up-swinging the latch dogs 17. The lower ends 13 of the support panels 10 are inserted into the receptor pan 40 and detachably secured thereto by the cooperating male and female pimples 14 and 43 associated with the support panels 10 and the receptor pan 40 respectively. The grate member 30, when dropped into the enclosure formed by erected panels 10 and 20, will automatically seat in rest position on the in-turned flanges 22 of the suspended panels 20.

Wood kindling placed upon the enclosed grate member 30 may be conveniently lighted through the upper end of the enclosure forming panels, and additional fuel such as charcoal, coke, coal or wood added to produce the desired heat. The top panel 50 mounted in position on the enclosure forming panels 10 and 20, may be moved laterally as desired to provide a draft opening *a* which insures combustion of the fuel at the desired rate. The plate section 51 of the top panel 50 also provides a hot plate on which food may be fried or broiled, or upon which a cooking utensil may be supported. This improved utility stove may also be provided with a suitable carrying handle 60 formed of wire, as shown in Fig. 9. The handle 60 is provided with hook portions 61 designed to be detachably inserted into suitable openings 29 formed in the adjacent upper end of the suspended panels 20. Thus the entire stove unit may be lifted and carried around at the camp location.

This improved utility stove is so shaped and formed as to permit the detachable parts thereof to be assembled into a flat and compact package, as shown in Figs. 10, 11 and 12, to facilitate storage and transportation thereof to and from the camp site. The suspended panels 20 are so shaped and formed that they can be snugly nested within the wall forming flanges 12 of one of the support panels 10, which thus serves as a tray member, as shown more particularly in Figs. 11 and 12. There is ample room between the flanges 12 of the tray forming support panel 10 to also receive the flat grate member 30 and the carrying handle 60. When the suspended panels 20 and the grate member 30 have been nested between the flanges 12 of the tray forming support panel 10, the other support panel 10 serving as a cover for the package, is telescoped together with the tray forming support panel, with the flanges 12 of the support panels arranged in overlapped relationship as shown in Fig. 12.

The flanges 42 of the receptor pan 40 are so spaced as to permit the receptor pan 40 to be snugly telescoped over one of the package forming support panels 10. The flanges 42 of the receptor pan have a slight inward camber or

spring, so as to frictionally embrace the outside flanges 12 of the telescoped support panels 10, with the base section 41 of the receptor pan 40 snugly seating over the outside face of adjacent wall section 11 adjacent the support panel. Likewise, the flanges 52 of the top panel 50 are so spaced as to snugly telescope over the other support panel 10, with the inwardly sprung flanges 52 thereof frictionally gripping and embracing a section of the flanges 42 of the receptor pan 40, as shown in Figs. 10 and 11. Thus the top panel 50, when in telescoped position, serves to grip and clamp the telescoped receptor pan 40 and the covering and tray forming support panels 10 together in a flat and compact assembly which can then be carried and transported as a unitary package.

This improved utility stove admirably serves the needs of sportsmen and campers by reason of its novel features of construction, which permits all the component parts thereof to be nested together in a compact rectangular package of minimum cubicle volume, adapted to be carried in the pocket of the camper or sportsmen. The component parts of the stove are inexpensive to fabricate, and provide a utility stove unit which can be manufactured and sold at relatively low cost. This improved stove unit is further designed for erection and assembly from package form in a matter of a minute or less, and when the parts thereof have been assembled and locked together, a sturdy and rigid heating and cooking unit is provided which admirably serves the comfort and convenience of the outdoor camper and sportsman.

While certain novel features of the invention have been disclosed herein, and are pointed out in the claim, it will be understood that various omissions, substitutions, and changes may be made by those skilled in the art without departing from the spirit of the invention.

What is claimed is:

A knock-down campers' utility stove comprising a pair of sheet metal support panels each

presenting a wall portion and side flange portions extending from the wall portion, a pair of opposite sheet metal suspension panels, means for detachably connecting said suspension panels to said support panels to provide a walled enclosure, said connecting means comprising heat resistant headed rivets spaced along the opposite side margins of each suspension panel operative to removably interlock into corresponding bayonet slots formed in the flange portions of said support panels, a receptor pan providing a base upon which said support panels are supported, said receptor pan having flange portions designed to receive and resiliently grip the lower ends of said support panels when seated within the receptor pan, a removable grate member fittable within the walled enclosure formed by the connected support panels and suspension panels, each of said suspension panels having an inturned flange adjacent the lower edge thereof providing a rest support for said grate member in spaced relation to said receptor pan, said suspension panels being of shorter length than said support panels providing a grate up-draft passage therebelow, and a top panel adapted to be removably supported on the upper ends of said connected support panels and suspension panels providing a hot plate for the assembled stove.

VICTOR R. WAGNER.
